United States Patent Office

Des. 182,474

Patented Apr. 8, 1958

182,474

COMBINED CHAIR AND DESK

William A. Mielke, Cleveland, Ohio

Application March 5, 1957, Serial No. 45,108

Term of patent 7 years

(Cl. D15—1)

FIG. 1

FIG. 2

FIG. 3

FIG. 4

Fig. 1 is a perspective view of a combined chair and desk showing my new design and illustrating the same as it appears in the chair position;

Fig. 2 is a side elevation of the combined chair and desk shown in Fig. 1;

Fig. 3 is a perspective view of a combined chair and desk showing my new design and illustrating the same when it is in a chair and desk position; and

Fig. 4 is a side elevation of the combined chair and desk shown in Fig. 3.

I claim:

The ornamental design for a combined chair and desk, as shown.
